LEG LENGTH ADJUSTING APPARATUS**Richard F. Derby, West Concord, and Arthur Biery,
Pine Island, Minn.****Application August 26, 1954, Serial No. 452,288****8 Claims. (Cl. 228—63)**

This invention relates to apparatus for attachment to an article having support legs for maintaining such article in substantially level position and for maintaining the support legs thereof in substantially upright position regardless of the contour of the supporting surface upon which such article is placed, and more specifically this invention relates to apparatus for substantially automatically adjusting the length of the legs of such an article depending upon the contour of the supporting surface upon which the legs are placed.

Many articles, such as stepladders, lawn chairs and tables, saw horses, extension ladders and the like are primarily designed for use out-of-doors and are to be placed upon the ground which frequently has an irregular contour. When such articles are placed upon such an irregularly contoured supporting surface not all of the support legs of such an article will engage the ground and therefore the article will assume a tilted position to cause all of the legs thereof to engage the ground and lend support thereto.

In the past some types of apparatus of the class described have been devised but have some serious disadvantages which prevented such types of apparatus from coming into widespread use. Generally such types of apparatus employ a leg-adjusting cord to substantially simultaneously adjust the relative position of the adjustable extension members of such apparatus. A major disadvantage of many of the known types of apparatus of the class described is that the weight of the article supported and the weight of any load placed on such an article is carried by the leg-positioning cord. Obviously such cords are thereby subjected to substantial wear and strain and, of course, when such a cord breaks as a result of the wear the leg-adjusting apparatus will substantially collapse to cause sudden and often disastrous tilting of the article supported thereby.

Another of the serious disadvantages of many types of apparatus of the class described is that the locking of the leg extension portions of the apparatus is not positive at all times. In these types of apparatus the leg extension portions are locked when a load is carried by the article supported by the legs, and when such load is removed, the leg-extension portions become unlocked and are permitted to retract to cause tilting and shifting of the article. This is especially disadvantageous when such types of apparatus are used with a stepladder where the leg-extension portions are securely locked when a man is on the ladder but become unlocked when he gets off the ladder, as onto a roof. If the ladder shifts before he again places his weight on the top of the ladder, a serious accident is very likely to occur when he places his weight upon the tilted ladder.

Therefore, it is to the solution of these and other disadvantages to which our invention is directed along with the inclusion therein of other novel features.

A general object of our invention is to provide a new and improved apparatus of relatively simple and inexpensive construction and operation for adjusting the lengths

2

of the support legs of an article depending upon the contour of the surface or terrain upon which the article is to be placed to maintain such legs in their normal substantially upright position.

5 Another object of our invention is to provide novel apparatus of the class described which will positively lock the support legs of such an article in extended position when the weight of such article is carried thereby and will be quickly released to permit adjusting of the length 10 of the legs when the weight of the article is removed from such support legs.

Still another object of our invention is to provide improved apparatus of the class described which will provide oppositely directed shifting of the extension portions 15 of the support legs when only one of the extension portions engages the ground and which will lock the leg extension portions in fixed vertical relation when both of the same engage the supporting surface and tend to shift upwardly with relation to the support legs.

20 These and other objects and advantages of our invention will more fully appear from the following description made in connection with the accompanying drawings wherein like reference characters refer to the same parts throughout the several views and in which:

25 Fig. 1 is a front elevation view of a pair of support legs embodying our invention and being partly broken away to show details thereof;

Fig. 2 is a detail view taken on a horizontal plane substantially at 2—2 of Fig. 1;

30 Fig. 3 is a detail section view taken on a horizontal plane substantially at 3—3 of Fig. 1;

Fig. 4 is a detail elevation view, partly in section, taken on a substantially vertical plane at 4—4 of Fig. 1; and

35 Fig. 5 is a detail sectional elevation view taken substantially at 5—5 of Fig. 4, and showing a portion of the apparatus of Fig. 1 in unlocked position.

As shown in Fig. 1 we provide a pair of substantially upright extendible and retractable support legs 10 and 11 which may be secured to an article such as a saw horse or extension ladder to support the same. Support legs 10 and 11 include support rails 12 and 13 or rail members which are rigidly interconnected by any suitable means, such as the article supported thereby, to positively maintain support rails 12 and 13 in fixed relation relative to each other.

45 Each of the support rails 12 and 13 are provided with a pair of apertures each being aligned with a corresponding aperture in the other support rail. Tubular members 14 and 15 are disposed in spaced apart relation between rail members 12 and 13 and are inserted into the aligned apertures thereof to provide a tubular interconnection therebetween. Tubular members 14 and 15 may be secured in the rail members 12 and 13 by any suitable means such as by crimping the end portions thereof, to form external retaining flanges 14a and 15a respectively.

50 A pair of rollers 16 having concavely curved guiding peripheral surfaces are provided, in the form shown, at the lower terminal portions of tubular member 14 and are suitably journaled to permit rotation thereof about an axis extending transversely of tubular member 14 and rail members 12 and 13.

55 Guiding means are provided on the lower end portions 12a and 13a of rail members 12 and 13 and in the form shown such guiding means comprise guide elements 17 and 18 in the form of eye bolts connected to the respective rail members 12 and 13 by any suitable means such as nuts 17a and 18a.

60 Support legs 10 and 11 also include a pair of upright rigid extension members 19 and 20 which, in the form shown, are constructed of a tubular metal material, and which are guided by guide elements 17 and 18 respectively for vertical sliding movement adjacent to and in spaced

relation with the respective support rails 12 and 13. Extension members 19 and 20 extend downwardly beyond the lower end portions 12a and 13a of the respective rail members 12 and 13 to engage the supporting surface S which may be irregularly contoured. Extension members 19 and 20 are provided at the lower end portions with enlarged feet 21 and 22. Ball sockets 19a and 20a are provided in the lower end portions of the extension members 19 and 20 to receive and swivelly and swingably mount the respective ball connections 21a and 22a of feet 21 and 22 respectively. A pair of stabilizing members 23 and 24, as best shown in Fig. 3 are secured to the upper end portions of the extension members 19 and 20 respectively. Stabilizing elements 23 and 24 are provided with laterally extending guiding flanges 23a and 24a which are disposed in proximity with the respective support rails 12 and 13 to be guided thereby to prevent turning of extension members 19 and 20 about their respective longitudinal axes.

A pair of locking elements 25 and 26, which in the form shown are constructed of a ferrous metal material, are swingably mounted on the respective support rails 12 and 13, and in the form shown are mounted between the respective guide elements 17 and 18 thereon. The locking elements 25 and 26 have locking rings 25a and 26a and elongated shanks 25b and 26b with slightly enlarged shoulder portions 25c and 26c interposed therebetween. The interior opening of the ring portions 25a and 26a may be slightly oblong in shape and are of such size to receive the respective extension members 19 and 20 in close fitting relation, allowing the same to slide freely therethrough. Rings 25a and 26a are disposed in laterally outstanding relation with the respective support rails and are provided with inner and outer gripping portions which, when locking elements 25 and 26 are swung in an upward direction, engage and frictionally grip the respective extension members 19 and 20. Tapered apertures 12b and 13b provide a restricted opening in an outward direction through the respective support rails 12 and 13 to receive the shank portions 25b and 26b of locking elements 25 and 26 respectively. The upper portions of apertures 12b and 13b are substantially horizontal to preclude locking elements 25 and 26 from swinging in a downward direction and the lower portions of said apertures are inclined to permit swinging of locking elements 25 and 26 upwardly into a locking position.

Actuating elements 27 and 28, which constitute magnets, are mounted in the respective side rails 12 and 13 above the respective locking elements to exert a force thereon to swing the same into substantially horizontal position wherein the extension members 19 and 20 will be unlocked. Of course a tension spring might be substituted for such magnets 27 and 28 as shown.

Locking actuators 29 and 30 comprise, in the form shown, metal plates, each of which are similarly constructed. As best shown in Fig. 4, locking plate 30 is provided with a pair of spaced apart elongated guide apertures or openings 30a which receive and are guided by the shanks of eye bolts 17 to permit restricted vertical movement of plate 30. Plate 30 also is provided with another aperture 30b in the upper end portion thereof which is substantially aligned with the opening of tubular member 15 and the respective aligned apertures of support rails 12 and 13. Locking plate 30 is also provided with an oblong laterally extending opening 30c in the central portion thereof between openings 30a to receive the shank portion 25b and shoulder portion 25c of locking element 25 therethrough. In closely spaced relation with and below opening 30c, an out-turned rigid lip 30d is provided for engaging the shoulder portion 25c of locking element 25.

A flexible interconnection 31 is secured to each of the extension members 19 and 20 and extends therebetween through the apertured support rails 12 and 13 to be

guided thereby, the upper portion 31a of flexible interconnection 31 extending through tubular member 14 and the lower portion 31b extending through the tubular member 15 and through the aligned apertures 29b and 30b of the respective locking actuators 29 and 30. In the form shown the flexible interconnection comprises an elongated flexible element such as a cord or flexible cable which is guided by the rollers 16 and which is secured to the stabilizing members 23 and 24 of the respective extension members 19 and 20.

Operation

In operation the article to which the extendible and retractable support legs 10 and 11 are secured will be generally lifted to move the same into a desired position. When the support legs 10 and 11 are raised, the weight of the extension members 19 and 20 is carried by the upper portion 31a of the cord 31 and the extension members 19 and 20 are both shifted downwardly slightly relative to the respective support rails 12 and 13 when tension is applied to the flexible cord 31. This will cause a slight downward shifting of the lower portion 31b of cord 31 which permits restricted downward shifting of locking actuator plates 29 and 30. Downward movement of the actuator plates 29 and 30 causes their respective out-turned lip portions 29d and 30d to disengage from the locking elements 25 and 26. The slight downward shifting of extension members 19 and 20 will also cause a swinging of locking elements 25 and 26 in downward direction causing the same to assume a substantially horizontal position substantially as shown in Fig. 5 wherein the extension members 19 and 20 are free to slide.

When the support legs 10 and 11 are again lowered toward the ground, one of the extension members 19 and 20 will engage the irregularly contoured supporting surface before the other extension member engages said surface. If only extension member 19 engages the supporting surface, it will be shifted upwardly with respect to support rail 12 to relieve tension on the upper portion 31a of cord 31 which allows extension member 20 to shift downwardly. The lower portion 31b of cord 31 may exert a slight downwardly directed pulling force of extension member 20 to aid in shifting thereof in a downward direction. Supporting legs 10 and 11 will be manually held in an upright position while extension member 19 is shifting upwardly and being retracted and while extension member 20 is being extended in a downward direction.

After some upward shifting of extension member 19 and downward shifting of extension member 20, extension member 20 will also engage the supporting surface. When the weight of the support legs 10 and 11 and of the article held thereby is placed upon the extension members 19 and 20, there will be a slightly downward shifting of support rails 12 and 13 with respect to the corresponding extension members 19 and 20 to relieve the tension in the upper portion 31a of flexible cord 31 and to tighten the lower portion 31b of cord 31. The tightening of the lower portion 31b of cord 31 is accomplished by a slight upward shifting thereof which causes a slight upward shifting of each of the locking actuators 29 and 30 and a corresponding upward shifting of the out-turned lips 29d and 30d thereof. Upward shifting of said lips causes them to engage the shoulder portions 25c and 26c of locking elements 25 and 26 to cause the same to be swung upwardly. The inner and outer locking portions of the locking elements engage and grip the extension members 19 and 20 in locking relation and prevent upward shifting thereof with respect to the corresponding support rails 12 and 13.

Of course it is obvious that the guide elements 17 and 18 could be replaced by a suitably arranged tubular guide housing which in addition to guiding would make the working apparatus more weather-proof to prevent deterioration thereof.

It will be seen that we have provided a new and improved apparatus of relatively simple and inexpensive construction and operation for adjusting and fixing the lengths of the support legs of an article to suitable lengths so as to maintain such legs in their normal upright position and to maintain such an article in level position without regard to the contour of the supporting surface upon which the article is to be placed.

It will also be apparent that we have provided novel apparatus for substantially simultaneously adjusting the different lengths of a pair of support legs when said legs are placed upon an irregularly contoured surface and which, when both of said legs engage such a surface, will positively lock such legs to restrict subsequent retraction thereof and to thereby maintain such legs in substantially normal upright position.

It will also be noted that we have provided improved leveling mechanism for an article to be placed upon an irregularly contoured supporting surface which mechanism is positively locked when the weight of the article is carried thereby and is quickly and surely released when the weight of the article is removed therefrom to provide ready and easy adjustment of the length of the legs of such an article.

It will, of course, be understood that various changes may be made in the form, detail, arrangement and proportion of the parts without departing from the scope of our invention which consists of the matter described herein and set forth in the appended claims.

What we claim is:

1. In a leveling apparatus for supporting an article on an irregularly contoured surface, the combination of a pair of extendible and retractable support legs adapted to carry such an article, each of said legs including an upright rail member rigidly secured to the rail member of the other leg, and each of said legs including an extension member disposed adjacent the corresponding rail member and extending downwardly therebeyond to engage such a supporting surface, guide means slidably interconnecting said extension members with the corresponding rail members to permit relative vertical shifting thereof, a pair of locking elements each respectively interposed between a corresponding rail member and extension member, each of said locking elements being fulcrumed on one of said members for vertical swinging and having oppositely facing gripping portions disposed on opposite sides of the corresponding extension member for frictionally engaging the opposite sides of a corresponding extension member upon tilting movement of said locking elements to positively lock the locking elements solely to the corresponding extension member, said locking elements including a portion for supporting said rail members, and a continuous flexible interconnection having upper and lower portions slidably carried by and extending between said rail members and having vertically movable side portions securely attached to each of said extension members, whereby said flexible interconnection will produce with displacement of one of said extension members oppositely directed displacement of the other extension member when the same engage such an irregular surface, whereupon the legs may be locked in position to maintain the same in substantially upright position.

2. The structure recited in claim 1 and including actuating members secured to the support rails adjacent to said locking elements and each of said actuating members exerting a force on the corresponding locking elements in a direction to swing the gripping portions thereof out of locking engagement with the corresponding extension members when the support leg is raised to remove the weight thereof from the extension member.

3. The structure recited in claim 1 and including a pair of stabilizing elements each fixedly secured to a respective extension member and extending laterally thereof into close proximity with the corresponding sup-

port rail to engage and be guided thereby to prevent turning of said extension member to preclude slipping in the frictional engagement between the extension member and the corresponding locking ring.

5 4. In apparatus for leveling an article to be placed upon an irregularly contoured surface, the combination of a pair of upright support rails attachable to such an article, a pair of extension members respectively disposed adjacent corresponding rails and extending downwardly therebeyond for engaging such a surface, guide means slidably interconnecting said support rails and the corresponding extension members to permit relative vertical shifting thereof, an elongated flexible element slidably carried by and extending between said support rails and having vertically movable portions, secured to each of said extension members, both of said vertically movable portions moving upwardly in response to upward movement of the extension members, a pair of rigid locking elements fulcrumed on respective support rails for vertical swinging and having oppositely facing gripping portions disposed on opposite sides of the corresponding extension member for frictionally engaging the opposite sides of a corresponding extension member upon tilting movement of said locking elements to positively lock the locking elements solely to the corresponding extension member, said locking elements including a portion for supporting said rail members, and actuating interconnections respectively connected with the vertically movable portions, said flexible element and said locking elements 10 and swinging said locking elements upwardly into gripping relation on said extension members when the extension members simultaneously engage such an irregular surface and are shifted upwardly with respect to said support rails.

20 5. In a leveling apparatus for supporting an article on an irregularly contoured supporting surface, the combination of a pair of rigidly interconnected upright support rails, each having spaced apart apertures and having lower end portions and each adapted to be secured to such an article, a pair of rigid extension members and each extending downwardly beyond the lower end portion of said support rails for engaging such an irregularly contoured supporting surface, a number of guide elements each slidably interconnecting one of said support rails and the corresponding extension member in spaced relationship, a pair of locking rings, means mounting one of said locking rings on each of said support rails to swing in a vertical direction and to extend outwardly therefrom in surrounding relation with the corresponding extension member, each of said locking rings having inner and outer gripping portions disposed on opposite sides of the extension member and being swingable upwardly into frictional gripping engagement therewith to thereby restrict vertical shifting thereof relative to the corresponding support rail, a pair of locking actuators each being guided on one of said support rails for restricted vertical movement, means engaging the corresponding locking ring to produce vertical swinging thereof, aligned apertures in said support rails each of said locking actuators having an aperture therein substantially aligned with one of the apertures in the corresponding support rail, and an elongated flexible element secured to said extension members and having an upwardly directed portion threaded through the apertures of said support rails and having a downwardly directed portion extending through the aligned apertures of said locking actuators and said support rails and producing with displacement of one of said extension members, oppositely directed displacement of the other extension member, and said elongated flexible element producing with simultaneous upward shifting of both of said extension members, upward shifting of said locking actuators to swing said locking rings into locking frictional engagement with the extension members to thereby restrict upward shifting thereof relative to said support rails.

6. The structure recited in claim 5 and said locking

rings being constructed of a ferrous metal material and a pair of magnets mounted in said support rails adjacent to said means mounting said locking rings and exerting a force thereon to swing the locking rings out of locking engagement when the support rails are raised to cause the weight of said extension members to move the same downwardly.

7. In a leveling apparatus for supporting an article on an irregularly contoured surface, the combination of a pair of rigidly interconnected depending rail members attachable to such an article, a pair of elongated extension members respectively disposed adjacent corresponding rail members and extending downwardly therebeyond, guide means slidably interconnecting said rail members and their corresponding extension members, a pair of locking elements each fulcrumed for vertical swinging on a respective rail member and having oppositely facing gripping portions disposed on opposite sides of the corresponding extension member for frictionally engaging the opposite sides of a corresponding extension member upon tilting movement of said locking elements to positively lock the locking elements solely to the corresponding extension member, said locking elements including a portion for supporting said rail members, actuating mechanism responsive to simultaneous upward movement of both extension members relative to the rail members for swinging said locking elements upwardly into frictional locking relation with the extension members, said mechanism including movable operating means interconnecting and producing simultaneous upward swinging of said locking elements and also including means engaging each of said extension members and connected with the operating means for moving the same in response to simultaneous upward movement of said extension members relative to

said rail members, whereby to lock said members together.

8. In a leveling apparatus for supporting an article on an irregularly contoured surface, the combination of a pair of rigidly interconnected depending rail members having lower end portions and being attachable to such an article, a pair of vertically slideable extension members respectively disposed adjacent corresponding rail members and extending downwardly therebeyond, guide means slidably interconnecting said rail members and the corresponding extension members, a pair of locking elements each fulcrumed on one of said rail members for vertical swinging and having oppositely facing gripping portions disposed on opposite sides of the corresponding extension member for frictionally engaging the opposite sides of a corresponding extension member upon tilting movement of said locking elements to positively lock the locking elements solely to the corresponding extension member, said locking elements including a portion for supporting said rail members, and operating means interconnecting said locking elements for simultaneously shifting the same into gripping positions and including a connection with each of said extension members for actuating said locking elements when said extension members are simultaneously shifted upwardly with respect to said rail members.
